FOREIGN PATENT DOCUMENTS

WO D 000679089 8/2007

Primary Examiner — Charles Hanson(74) *Attorney, Agent, or Firm* — Victor Tsu(57) **CLAIM**

The ornamental design for an oral dosage form, as shown and described.

DESCRIPTION

FIG. 1 is a front right bottom perspective view of an oral dosage form showing our claimed design;

FIG. 2 is a front plan view of FIG. 1;

FIG. 3 is a left side view of FIG. 1, the right side view being a substantial mirror image thereof;

FIG. 4 is a top side view of FIG. 1, the bottom side view being a substantial mirror image thereof;

FIG. 5 is a front right bottom perspective view of an oral dosage form showing a second embodiment;

FIG. 6 is a front plan view of FIG. 5;

FIG. 7 is a left side view of FIG. 5, the right side view being a substantial mirror image thereof;

FIG. 8 is a top side view of FIG. 5; and,

FIG. 9 is a bottom side view of FIG. 5.

The evenly spaced broken lines showing is included for the purpose of illustrating environment and the dot-dot-dash lines represent the bounds of the claimed design both of which form no part of the claimed design.

1 Claim, 8 Drawing Sheets(56)
